UNITED STATES PATENT OFFICE.

WILHELM G. CARLSON AND OTTO JOHNSON, OF JAMESTOWN, NEW YORK, ASSIGNEES
TO THE FURNITURE HARDWARE CORPORATION, OF JAMESTOWN, NEW YORK, A
CORPORATION OF NEW YORK.

DESIGN FOR A DRAWER PULL.

Application filed July 16, 1927. Serial No. 22,789. Term of patent 3½ years.

To all whom it may concern:

Be it known that we, WILHELM G. CARLSON and OTTO JOHNSON, citizens of the United States, residing at Jamestown, in the county of Chautauqua and State of New York, have invented a new, original, and ornamental Design for Drawer Pulls, of which the following is a specification, reference being had to the accompanying drawing, forming part thereof, and in which—

Fig. 1 is a front elevation of our newly designed drawer pull; and

Fig. 2 is a side elevation of the design shown in Fig. 1.

We claim:

The ornamental design for a drawer pull as shown.

WILHELM G. CARLSON.
OTTO JOHNSON.
